COMBINED DEFROST PAN AND
STORAGE TRAY

Ray C. Sandin, Oak Park, Ill., assignor to General Electric Company, a corporation of New York

Application December 26, 1951, Serial No. 263,359

6 Claims. (Cl. 62—103)

1

This invention relates to an improved defrost pan for refrigerators, and has for a principal object the provision of a novel defrost pan having an external storage rack or tray for conveniently accommodating a plurality of small articles.

The need for providing means for storing small articles on other than the conventional refrigerator shelves has long been recognized, and it has become common to provide racks or shelves on the inner liner of the cabinet door to accommodate eggs, cans of milk or other foods, and the like. The trend has been toward the design of door shelves for specialized purposes; for example, some shelves are intended for egg storage and some for bottles; jars of "left-overs," and other relatively large articles. There is a practical limit to the storage capacity of such shelves, and the number which may be mounted on a door panel; and it is therefore an object of the invention to provide other and readily accessible facilities for the storage of small items such as eggs, small cans of food, etc., thereby effectively increasing available door shelf space for the accommodation of other items.

In particular, it is an object of the invention to provide an improved defrost pan having a shelf or bin extending across a predetermined extent of the front wall thereof, to provide means for storing such small articles.

It is another object of the invention to provide a small-article storage tray at a location which is readily accessible upon opening the cabinet door.

It is a further object of the invention to provide a combined defrost pan and small-article storage tray which functions without interference of the normal function of the defrost pan as a baffle for establishing proper air circulation within the refrigerator.

It is still another object to provide a defrost pan or the like having a front shelf or bin which may be removed without disturbing its contents when it is necessary to empty defrost water from the pan.

Other features and advantages of the invention will be understood from the following detailed description of an embodiment thereof, read in the light of the accompanying drawing, in which Fig. 1 is a front elevation of the upper portion of a refrigerator cabinet showing an application of the invention; Fig. 2 is a fragmentary side sectional elevation of the front portion of the defrost pan and the removably mounted tray taken on lines 2—2 of Fig. 1; and Fig. 3 is a fragmentary plan view of said pan and tray,

2

with the side wall of the refrigerator cabinet in section on lines 3—3 of Fig. 2.

In Fig. 1, a refrigerator 1 has the usual cabinet space 2 and an outer door 3, said door being shown in full open position. The refrigerator is represented as being of the type in which the evaporator 4—or alternatively, a frozen food storage compartment—extends across the full width of the cabinet. Said evaporator, or compartment, has a door 5 suitably hinged to afford access.

It is a standard practice to provide a shallow pan beneath the evaporator to catch drippage therefrom during defrost periods. Said pans are used as baffles to control air circulation within the cabinet, and accordingly, are spaced suitably below the bottom of the evaporator. The dimensions of the defrost pan are such that there is suitable side wall clearance between the pan and the sides and rear of the inner liner forming the refrigerator compartment. Warm air flowing up the front and sides of the cabinet gives up its heat to the evaporator, and the chilled air flows down along the rear and rear side walls into the cabinet space.

The shallow defrost pan 6—sometimes known as a chiller tray—preferably has a width at least equal to that of the evaporator 4 and a length sufficient to project slightly beyond the rear wall (not shown) of the evaporator, thus providing sufficient catch-basin area to receive water which may drip from the sides and rear of the evaporator during defrosting. The pan is suitably supported for withdrawal from the front; the rails 7 fixed to the respective sides 8 of the cabinet liner are merely representative of any suitable supports. Where the rails 7 terminate at the front of the pan, suitably headed studs 7.1 may be secured at suitable intervals to the side walls 8 to project over the sides of the pan and thus support the same against tilting under the weight of the contents of the storage tray, as later described. There is substantial clearance between the bottom of the evaporator and the pan 6.

As appears in Fig. 2, the front wall 9 of the pan terminates rearwardly of the front of the evaporator and each of the side walls 10 projects forwardly of said front wall to provide rigid extensions 10.1. In the presently preferred embodiment, these extensions afford means for the attachment of the storage tray or rack 12, although the tray may be entirely separate and supported on the rails 7 or equivalent. As shown, however, the tray may be molded from suitable plastic or metal to have rearwardly extending

side walls 14 in closely overlapping relationship with the pan wall extensions 10.1. Where tray 12 is to have a permanent connection with said pan wall extensions, the securement thereto might be by welding, if the respective walls were of metal, or by suitable adhesive, rivets, or the like, if the respective parts were each of plastic, or one of plastic and the other of metal. I consider it preferable, however, to mount the tray 12 removably on the pan extensions 10.1. One manner of effecting such removable mounting is to provide the respective extensions 10.1 with aligned slots 15 and to secure to the walls 14 of the tray an angle bracket having a base 16 and an inwardly and downwardly projecting plate 17. Said plate is designed to seat snugly within the associated slot 15. Such an arrangement supports the tray 12 against tilting relative to the pan 6. Obviously, the slots may be provided on the walls 14 and the pan wall extensions 10.1 have the cooperating mounting plates; other arrangements for detachable securement will occur to those skilled in the art.

It is not necessary, of course, to have the tray 12 extend the full width of the pan. Where a partial extension is desired, the tray support may include one of the side wall extensions 10.1 and a similar support-forming wall or extension (not shown) projecting forwardly from the front wall 9 of the tray.

The tray has a downwardly sloping top wall 18 which extends rearwardly into overlapping relation with the front wall 9 of pan 6, and thus catches and deflects into said pan any drippage from the extreme front portion of the evaporator. Further, the tray has the respective rear, bottom, and front walls 20, 21, and 22, defining a storage cavity bounded at each end by side wall portions 23. At least the front wall 22 may be foraminated, if desired, to provide for air circulation about the articles carried by the tray. A suitably decorated trim strip 24 may be overlaid on the front wall 22 if desired. It is important to note that the rear tray wall 20 is spaced well forwardly of the front pan wall 9 and that the wall 18 is substantially above the upper edge of said front pan wall. Such spacing provides an adequate air flow passage from the compartment 2 into the space between the pan and the bottom of the evaporator. The curved transition between walls 20 and 21, and the forward slant of wall 9, provided a throat of Venturi contour for the flow of air therethrough.

It will thus be seen that I have increased the utility of the usual drip pan by providing storage means in a portion of the cabinet which had hitherto been generally wasted. The pan functions as an air flow baffle and drip collector are unimpaired. To remove the pan for pouring defrost water therefrom, it is necessary only to draw the pan forwardly on its rails or guides 7 until tray 12 clears the front door 5, after which the tray may be removed without disturbing its contents, here shown as comprising a quantity of eggs E. The side walls 14 and 23 of the tray provide stability when the tray is placed on a counter or table. Pan 6 may then be entirely withdrawn, emptied and replaced, and the tray 12 restored to position before the pan is returned fully to its home position.

While there has been described what is at present considered to be the preferred embodiments of the invention, it will be understood that various modifications may be made therein, and it is intended to cover in the appended claims all

such modifications as fall within the true spirit and scope of the invention.

I claim:

1. In combination, a refrigerator defrost pan having spaced wall portions extending forwardly of a front wall thereof, and a tray-forming structure secured to and extending between said extending wall portions, the rear wall of said tray-forming structure being spaced forwardly of said pan front wall; said tray-forming structure having a top wall spaced above said pan front wall and sloping rearwardly and downwardly into overlapping relation therewith.

2. In combination, a refrigerator defrost pan having spaced wall portions extending forwardly of a front wall thereof, and a tray-forming structure extending between said extending wall portions in detachable securement thereto, the rear wall of said tray-forming structure being spaced forwardly of said pan front wall; said tray-forming structure having a top wall spaced above said pan front wall and sloping rearwardly and downwardly into overlapping relation therewith.

3. In combination, a refrigerator defrost pan having spaced wall portions extending forwardly of a front wall thereof, and a tray-forming structure secured to and extending between said extending wall portions in spaced relation to the front wall of the pan; the front wall of the pan sloping forwardly and the rear and bottom walls of said tray-forming structure sloping toward and then away from said pan front wall to provide an air-flow throat having a substantially Venturi shape in cross section.

4. In a refrigerator having a cabinet and an evaporator in an upper portion thereof to chill the cabinet space by heat exchange with air circulating within said cabinet, the combination of a substantially horizontally disposed baffle member supported within said cabinet and extending rearwardly therein below and in spaced relation with the bottom of said evaporator and a food-storage tray secured to said baffle in spaced relation with the front wall thereof; a rear wall of said tray cooperating with a front wall portion of said baffle member to provide a passage for air flow from said cabinet into the area between the bottom of said evaporator and said baffle member.

5. In a refrigerator having a cabinet and an evaporator in an upper portion thereof to chill the cabinet space by heat exchange with air circulating within said cabinet, the combination of a baffle-forming pan supported within said cabinet in parallel spaced relation with the bottom of said evaporator and a food-storage tray secured to said pan in spaced relation with the front wall thereof; the front wall of said pan being disposed rearwardly of the front portion of said evaporator, and a rear wall of said tray cooperating with said pan front wall to provide a passage for air flow from said cabinet into the area between the bottom of said evaporator and said pan, said tray, further, having a wall above said air flow passage and sloping rearwardly from beneath the front portion of said evaporator into overlapping relation with the front pan wall to conduct drippage from said evaporator into said pan.

6. In a refrigerator having a cabinet and an evaporator in an upper portion thereof to chill the cabinet space by heat exchange with air circulating within said cabinet, the combination of a baffle-forming pan removably supported within said cabinet in parallel spaced relation with the

bottom of said evaporator and a food-storage tray removably secured to said pan in spaced relation with the front wall thereof; the front wall of said pan being disposed rearwardly of the front portion of said evaporator and a rear wall of said tray cooperating with said pan front wall member to provide a passage for air flow from said cabinet into the area between the bottom of said evaporator and said pan, said tray, further, having a wall above said air-flow passage and extending the length of said front pan wall to divert drippage from said front evaporator portion into said pan.
